DESIGN FOR A SEMIRIMLESS SPECTACLE

Raymond F. E. Stegeman, Greece, N. Y., assignor
to Bausch & Lomb Optical Company, Rochester, N. Y., a corporation of New York

Application July 1, 1949, Serial No. 3,661

Term of patent 14 years

(Cl. D57—1)

To all whom it may concern:

Be it known that I, Raymond F. E. Stegeman, a citizen of the United States and a resident of the town of Greece, county of Monroe, and State of New York, have invented a new, original, and ornamental Design for a Semi-Rimless Spectacle, of which the following is a specification, reference being had to the accompanying drawing, forming a part thereof.

Fig. 1 is a front elevational view of a semi-rimless spectacle, showing my new design.

Fig. 2 is a top plan view thereof.

The characteristic features of the design are shown in full lines on the drawing.

I claim:

The ornamental design for a semi-rimless spectacle, substantially as shown and described.

RAYMOND F. E. STEGEMAN.
